Application September 16, 1939, Serial No. 295,204

7 Claims. (Cl. 29—16)

This invention relates to the manufacture of tie-plates and more particularly to a novel method and apparatus for punching such plates.

One form of rail fastening now in use includes a tie plate, usually of the double shoulder type made of rolled steel, in the end portions of which are openings disposed outwardly from the rail seat, each opening being adapted to receive a resilient rail lock and a tie-penetrating member, such as a spike. The spike coacts with the plate opening, the tie and the rail lock to retain the rail in its operative position with a spring action and resiliently lock the assembled parts together for dampening vibrations, minimizing destructive wear and loosening of contiguous parts, and for other purposes. In such a rail fastening, the tie plate moves vertically relative to the spikes, and in resisting longitudinal movement of the rail high pressures are set up between the plate and the sides of the spikes. In order to reduce the wear of the parts, it is desirable to provide for the spikes large bearing areas which are greater in height than the thickness of the plate adjacent to the spikes. It has been proposed heretofore to provide on the plate a supplemental bearing for each spike by indenting the plate bottom so as to raise a buttress on the top of the plate adjacent the outer face of the spike. However, this practice does not accomplish the desired objective of increasing the outer bearing for the spike, because the indenting of the plate bottom removes metal which would otherwise lend lateral support to the spike. In fact, due to the flow of metal incident to compression caused by the indenting operation, the resulting spike bearing area is of a height less than the thickness of the plate where the indenting is performed. Also, no increased bearing is afforded to the sides of the spikes transversely of the plate.

One feature of the present invention resides in the provision of enlarged bearing areas for the spikes or other tie-penetrating members by a novel method of punching tie plates, whereby an opening is formed in which the spike is positioned centrally of the opening and the lock by the sides of the opening. In a tie plate made in accordance with the invention, a supplemental bearing area in the form of a buttress is raised above the top surface of the plate outwardly of the spike so as to provide a bearing area for the spike equal in height to the thickness of the plate plus the height of the raised portion. Preferably, the plate opening is punched in a T-shape so that the spike may be centrally positioned by the stem of the T, and if desired, the sides of the stem

adjoining the spike may also be raised above the top surface of the plate to provide for the spike additional bearing areas extending lengthwise of the plate.

Another feature of the invention resides in the provision of a novel method of punching tie-plates by the practice of which the plate opening and the buttress for the spike may be formed in a single punching operation but without displacing metal from the bottom of the plate under the buttress. Thus, in a plate made by the new method the spike backing extends from the bottom of the plate to the top of the projecting buttress and is therefore more effective than the spike backing in plates as punched heretofore.

According to our new method, a slug of metal is first punched from the plate to form an opening somewhat smaller than the desired opening in the finished plate, the slug being preferably removed by a punch having a working end of the proper dimensions. In the same punching operation, the plate bottom on the side of the opening opposite the rail seat is depressed and the displaced metal is forced toward the top of the plate and at the same time outwardly from the opening into a recess in the die. This displacement of metal may be conveniently effected by a shoulder on the punch which is inclined so as to produce an outward component of force on the depressed metal and thereby cause a controlled, outward flow of metal into the recess. As the punch continues its movement through the plate, the metal flowing outwardly under the action of the inclined shoulder fills the recess in the die so as to form the desired buttress, and thereafter any surplus metal directly under the shoulder is sheared off in a second slug. Thus, the shoulder acts simultaneously to enlarge the plate opening to the desired size and to direct the metal removed for this purpose to the top of the plate at the outer edge of the enlarged opening where it may engage the spike directly under the head.

An undercut or indent for receiving part of the rail lock is preferably formed in the same punching operation by another shoulder properly positioned on the punch. The metal displaced in the indenting operation may be directed into an appropriate recess in the die to form a seat on the top of the plate for the lock.

For a better understanding of the invention, reference may be had to the following detailed description taken in conjunction with the accompanying drawings illustrating one form of ap-

paratus for practicing the new method. In the drawings

Fig. 1 is a sectional view showing a tie-plate mounted on a die in position to be punched;

Figs. 2, 3, 4 and 5 are similar views showing different stages of the punching operation;

Fig. 6 is a plan view of the die;

Fig. 7 is an end view of the punch;

Fig. 8 is a plan view of part of a tie-plate made in accordance with the new method;

Fig. 9 is a view similar to Fig. 1 showing a modified form of the die;

Fig. 10 is a plan view of the die shown in Fig. 9, with the tie-plate removed;

Fig. 11 is a sectional view on the line 11-11 in Fig. 10;

Fig. 12 is a plan view of part of a tie-plate punched with the apparatus shown in Fig. 9, and

Fig. 13 is a sectional view on the line 13-13 in Fig. 12.

The apparatus, as illustrated, comprises a die 10 having an opening 11 of approximately the size and shape of the desired opening in the tie-plate and which leads into an enlargement 12 in the bottom of the die. The top of the die on one side of the opening is formed with a recess 13, preferably extending across the face of the die and having a flat bottom 14 leading into the opening 11, and an inclined wall 15 leading outwardly from the bottom. At the opposite side of the die opening is another recess 16, preferably extending across the face of the die parallel to the recess 13 and having a flat bottom 17 sloping slightly downwardly from the opening 11 to a substantially vertical side-wall 18. The die 10 may be mounted in a holder 19 forming with the die a seat for a tie-plate 20 which is inverted on the seat so that the rail-abutment shoulder 21 lies flat against the vertical wall 18 and partly fills the recess 16.

Above the die is a punch 23 mounted in a suitable power driven holder 24 operable to force the punch through the tie-plate. The punch, as shown, is provided with an initial, plate engaging end 25 adapted to fit into the die opening 11 but which is somewhat smaller than the die opening. More particularly, the lower end 25 of the punch overlies all of the die opening 11 except a part of the opening adjacent the recess 13, this part of the opening being offset laterally from the punch end 25. Above its lower end, the punch is provided on one side with a downwardly facing shoulder 26 which is preferably inclined outwardly. This shoulder overlies the part of the die opening 11 adjacent the recess 13, and the outer edge of the shoulder is directly above the edge of the die opening 11 adjacent this recess, so that the end 25 of the punch and the shoulder 26 are adapted to fit closely in the die opening. Above the shoulder 26 but on the opposite side of the punch is a second shoulder 27 overlying the recess 16.

In the practice of the new method with the apparatus shown, a slug of metal 30 is first punched from the plate, preferably while the latter is at a forging temperature, by forcing the end 25 of the punch into the plate over the die opening 11. The slug 30 thus removed is considerably smaller than the die opening 11 and falls through this opening and the enlargement 12. The opening in the tie-plate is then enlarged by the action of the shoulder 26, and the metal removed incident to the enlarging operation is directed into the recess 13, as shown in Figs. 3 and 4. That is, when the shoulder 26

engages the bottom of the tie-plate, it displaces the metal directly beneath it and forces the metal downwardly and outwardly from the opening into the recess 13, this action being accentuated by the inclination of the shoulder 26 which produces a lateral component of force on the metal displaced from beneath it. The recess 13 is thus completely filled with metal removed from the plate opening, and the latter is enlarged from the bottom of the plate to the top. When the recess 13 is filled, any excess metal beneath the shoulder 26 is sheared off in a second slug 31 by the outer edge of the shoulder 26.

During the downward movement of the punch, the second shoulder 27 engages the tie-plate over the recess 16 and indents the plate bottom, as shown in Figs. 4 and 5. The metal displaced by this second shoulder is forced downwardly into the recess 16 so as to completely fill the latter and provide a built-up portion on the top of the plate adjacent the shoulder 21. It will be observed that before the indenting operation commences, the lower end 25 of the punch passes below the bottom of the recess 16, so that metal displaced by the shoulder 27 can pass only into unoccupied space in the recess 16 and cannot pass inwardly into the opening 11.

The new method may be performed rapidly to provide in a single punching operation an undercut opening 32 in the tie-plate and a pair of opposed buttresses 33 and 34 on opposite sides of the plate opening. Also, the method may be performed with an apparatus of simple form wherein the shoulder 26 on the punch performs the dual function of enlarging the plate opening from the bottom of the plate to the top thereof and at the same time directing the metal removed for this purpose downwardly and outwardly into the recess 13 to provide the buttress 34. The second shoulder 27 on the punch may be arranged to engage the plate bottom either before the recess 13 is completely filled or after the second slug 31 is sheared, but we prefer to engage the shoulder 27 with the plate bottom some time before the recess 13 is filled, so that the two buttresses 33 and 34 are formed substantially simultaneously and the two shoulders on the punch exert counterbalancing forces on the plate. In a tie-plate made in accordance with the new method, the plate bottom adjacent the undercut opening is not indented, and, accordingly, a spike in the plate opening is braced outwardly thereof from the bottom of the plate to the top of the buttress 34. While the die and punch, as shown, are formed to provide a T-shaped opening in the plate, it will be apparent that they may be formed to punch an opening of any other desired shape.

The apparatus shown in Fig. 9 is similar to that shown in Fig. 1, except that the die 10 is formed with recesses 36 communicating with the recess 13 and extending at right angles thereto along the stem of the T-shaped opening 11. The recesses 36, as shown, are provided with sloping side walls and have flat bottoms 37 leading into the opening 11 at the same level as the bottom 14 of the main recess 13. The plate 20 is placed on the die bottom side up and the punch 23 forced through the plate, preferably while the latter is at a forging temperature. The lower end 25 of the punch removes a slug of metal over the die opening 11, and when the shoulder 26 of the punch moves into the plate so as to enlarge the opening, metal is displaced into the recess 13, as described in connection

with the apparatus shown in Fig. 1. At the same time, additional metal is displaced into the side recesses 36, so that when the punch has moved to the lower limit of its travel, the recesses 13 and 36 are filled with metal displaced by the punch. If desired, the punch may be provided with additional shoulders similar to the shoulder 26 but facing the recesses 36, so as to supplement the action of shoulder 26 in displacing metal into these side recesses. Also, the volume of recess 13 and the effective area of shoulder 23 may be proportioned so that the amount of metal displaced by this shoulder is sufficient to fill the recesses 13 and 36.

When the punching is completed, the metal filling the recesses 36 forms raised buttresses 38 integral with the buttress 34 and extending along the opposite sides of the stem of opening 32 in the plate. These buttresses 38 increase the area of contact between opposite sides of the spike and the tie-plate so as to reduce wear of the parts, and they also act to guide the spike as it is driven through the plate opening 32 into the tie. In addition, the buttresses 38 form with buttress 34 a U-shaped raised portion on the plate for engaging the spike on three sides, and the buttresses 38 act to strengthen the buttress 34.

We claim:

1. In the manufacture of tie-plates having an opening therein, the method which comprises punching a slug of metal from the plate to form an opening smaller than the final opening, enlarging the opening from the bottom of the plate to the top thereof and directing the metal removed for this purpose to the top of the plate at the outer edge of the enlarged opening, and indenting the plate bottom at the opposite edge of the opening.

2. In the manufacture of tie-plates having an opening therein, the method which comprises punching a slug of metal from the plate to form an opening smaller than the final opening, enlarging the opening from the bottom of the plate to the top thereof and directing the metal removed for this purpose to the top of the plate at the outer edge of the enlarged opening, and indenting the plate bottom at the opposite edge of the opening and directing the displaced metal toward the top of the plate to form a built-up portion on the plate at said opposite edge of the opening.

3. In the manufacture of tie-plates with the use of a die, the method which comprises placing a tie-plate on the die with the top surface of the plate resting on the die, punching a slug of metal from the plate into the die to form an opening in the plate, enlarging the plate opening from the bottom of the plate to the top thereof and directing the metal removed for this pur-

pose outwardly and downwardly into the die to form a buttress on the top of the plate, and shearing off the excess metal removed from the enlarged opening after the recess is filled.

4. In the manufacture of tie-plates with the use of a die, the method which comprises placing a tie-plate on the die with the top surface of the plate resting on the die, punching a slug of metal from the plate into the die to form an opening in the plate, enlarging the plate opening from the bottom of the plate to the top thereof and directing the metal removed for this purpose outwardly and downwardly into the die to form a buttress on the top of the plate, and indenting the plate bottom at the edge of the plate opening opposite said buttress during the formation of the buttress.

5. In the manufacture of tie-plates with the use of a die, the method which comprises placing a tie-plate on the die with the top surface of the plate resting on the die, punching a slug of metal from the plate into the die to form an opening in the plate, enlarging the plate opening from the bottom of the plate to the top thereof and directing the metal removed for this purpose downwardly and outwardly into the die to form a buttress on the top of the plate, and indenting the plate bottom adjacent the opening and directing the displaced metal into the die to form a second buttress on the plate opposite said first buttress.

6. In the manufacture of tie-plates, the method which comprises punching a slug of metal from the plate to form an opening therein, displacing metal adjacent the outer edge of the opening to raise above the top surface of the plate a buttress for a tie-penetrating member in the opening, and indenting the plate bottom adjacent the opposite edge of the opening and directing the displaced metal toward the top of the plate to form a built-up portion on the plate at said opposite edge of the opening.

7. In the manufacture of tie plates having an opening therein, the method which comprises punching a slug of metal from the plate to form an opening smaller than the final opening, depressing the plate bottom adjacent one edge of the opening and directing the displaced metal outwardly from the opening from the bottom of the plate toward the top thereof, positively arresting the movement of the displaced metal toward the top of the plate, thereby forming a buttress on the plate and simultaneously enlarging the opening from the bottom of the plate to the top thereof, and shearing off the excess metal in said opening after said movement is arrested.
